UNITED STATES PATENT OFFICE.

IRA E. STUMP, OF CLEVELAND, OHIO, ASSIGNOR TO HUGH PEASE, OF LAKEWOOD, OHIO.

SIGNAL-HORN.

1,034,530.

Specification of Letters Patent. Patented Aug. 6, 1912.

Application filed May 18, 1911. Serial No. 627,963.

To all whom it may concern:

Be it known that I, IRA E. STUMP, a citizen of the United States, residing at Cleveland, in the county of Cuyahoga and State 5 of Ohio, have invented certain new and useful Improvements in Signal-Horns, of which the following is a specification.

My invention relates to improvements in signal horns, and is particularly designed 10 and adapted for use as an exhaust blown signal horn for use in connection with automobiles, motor trucks, motor boats, and the like. When used as an exhaust blown signal horn in connection with automobiles, the 15 same is preferably connected to the exhaust pipe between the engine and the muffler, and when so used the improved horn is adapted to provide a combined signal horn and cut-out valve, the rotary valve being adapted to 20 be moved from its normal or nondiverging position to either a fluid diverting cut-out position or a fluid diverting whistle or horn sounding position as desired.

With the above mentioned and other ends 25 in view, the invention consists in the novel construction, arrangement, and combination of parts, hereinafter described, illustrated in one of its embodiments in the accompanying drawings, and particularly pointed out 30 in the appended claims.

Referring to the drawings, forming a part of this specification, Figure 1, is a top plan view of the improved signal horn, the parts being shown in their normal or nondiverging 35 positions. Fig. 2, a side elevation of the same, the dotted lines indicating the position of the improved rotary valve and hood when in their fluid diverting or horn sounding position. Fig. 3, an end view of the 40 same. Fig. 4, a longitudinal sectional view, taken on line 4-4 of Fig. 1, the dotted lines indicating the intermediate or fluid diverting cut-out position of the parts. Fig. 5, a perspective view of the improved rotary 45 valve detached.

Similar numerals of reference designate like parts throughout all the figures of the drawings.

The improved signal horn comprises a 50 main conduit or pipe body 1, adapted to be suitably connected to and form a part of the exhaust pipe leading from the engine, said main conduit 1, preferably comprising two parts provided with connecting flanges 55 ^{1a}, secured together by means of a plurality of rivets 2. The main conduit 1, is provided

with a fluid discharge opening 3, normally closed by means of a rotary valve 4, when the latter is in its nondiverging position. A supplemental conduit or horn body 5, is 60 adapted to be thrown into and out of communication with the main pipe body 1, through the medium of the rotary valve 4, said horn body or pipe being provided with a whistle slot 6, or second fluid discharge 65 opening immediately above the fluid discharge opening 3, said horn body 5, being provided with attaching flanges 5a, secured to the flanges 1a, of the pipe body by the rivets 2, which secure the latter together. 70

As a means for operating the rotary valve 4, whereby the latter may be moved to its fluid diverting cut-out position as shown in dotted lines in Fig. 4, or to its fluid diverting whistle sounding position as shown in 75 dotted lines in Fig. 2, as well as providing means for modifying the pitch of the horn when in the latter position, a rotary hood 7, is mounted upon and secured to the ends of the bearing pin or shaft 8, extending 80 through the sides of the supplemental conduit or horn body 5, whereby the rotary valve 4, and hood 7, are simultaneously rotated or operated, as hereinafter described, and whereby the valve 4, and hood 7, are 85 adapted to simultaneously open and close the fluid discharge opening 3, and whistle slot 6.

When the rotary hood 7, and valve 4, are moved to their fluid diverting whistle sounding positions as indicated in dotted lines in 90 Fig. 2, it will be observed that the front portions 7a, of the sides of the hood will extend and project above the sides of the whistle slot forming tone modifying elements adapted to co-operate with the whistle slot in controlling the pitch and tone of the horn when the latter is being operated or sounded by the passage of the operating fluid or exhaust gases through the passage 9, (see Fig. 100 2) leading to the lip of the whistle slot 6.

As a means for moving the rotary valve 4, to its various diverting positions whereby communication is established between the pipe bodies 1, and 5, and to its normal or 105 nondiverting position whereby communication between said pipe bodies is cut off a chain or cable 10, is attached to a cross bar or member 11, of the rotary hood 7, said chain or cable being connected to a foot lever or other suitable operating device adapted to move the rotary hood and valve 110

against the resistance of a coiled spring 12, the latter being adapted to return and hold the parts to their normal position when the pressure upon the foot lever or operating device is released.

When the rotary valve 4, is moved to its intermediate or fluid diverting cut-out position, as indicated by dotted lines in Fig. 4, it will be observed that the operating fluid 10 will be permitted to be diverted from the inlet portion of the pipe body 1, upwardly and over the rotary valve 4, passing out through the whistle slot 6, and through the supplemental conduit or horn body 5, thus 15 providing a cut-out or relief valve for use as occasion demands.

From the foregoing description, taken in connection with the accompanying drawings, the operation and advantages of my 20 invention will be readily understood.

Having thus described an embodiment of my invention, what I claim and desire to secure by Letters Patent is,—

1. In a signal horn the combination with

a pipe body provided with a fluid discharge 25 opening and a horn body provided with a whistle slot above said opening; of a rotary valve mounted in and normally closing said opening and adapted to open the latter and having two wings adapted to extend across 30 said pipe and horn bodies and to assume a fluid diverting whistle sounding position with respect to said whistle slot and horn body.

2. A signal horn, comprising a main conduit provided with a fluid discharge opening, a horn body communicating with said fluid discharge opening and provided with a whistle slot, and a rotary valve and hood pivoted from a common point and adapted 40 to simultaneously open or close said fluid discharge opening and whistle slot.

In testimony whereof I have affixed my signature in presence of two witnesses

IRA E. STUMP.
